UNITED STATES PATENT OFFICE.

LIONEL WORSLEY HUGHES, OF LONDON, ENGLAND.

PACKING-CASE.

1,383,401.

Specification of Letters Patent.

Patented July 5, 1921.

Application filed February 8, 1921. Serial No. 443,428.

To all whom it may concern:

Be it known that I, LIONEL WORSLEY HUGHES, a subject of the King of England, residing at Raymond House, 32 Theobalds road, London, W. C. 1, England, (whose post-office address is Raymond House, 32 Theobalds road, London, W. C. 1, England,) have invented certain new and useful Improvements in Packing-Cases, of which the following is a specification.

This invention relates to an improvement in or modification of the means for fastening packing cases described in the specification of my United States Patent No. 1,345,856 and has for its object to simplify the construction.

According to my aforesaid United States Patent No. 1,345,856 the hinged fastening strips each terminate in an apertured disk 20 or plate which lap over a bolt at the center of the lid of the case. By such overlapping it follows that the strips make an inconveniently thick joint at the center of the lid and they could only be lifted, when 25 opening the case, in a predetermined sequence.

My present improvement is designed to obviate both these disadvantages.

In the accompanying drawings:—

Figure 1 is a perspective view of a packing case with fastenings according to my present invention;

Fig. 2 is a partial section to an enlarged scale taken on the line 2—2 of Fig. 1 with 35 one of the fastening strips removed; and

Fig. 3 is a part plan view, also enlarged, of Fig. 1.

In these drawings A is the packing case, D the strengthening bands and D' the fastening strips hinged thereto as before. Each fastening strip D' terminates in a plate D² as before which is now made with tapered sides D⁴ cut away toward the apex as shown at D⁵ in Fig. 3 so that when all are closed 45 down they leave an aperture D³ in the center through which passes the bolt E. The tapered plates may be stepped inward as shown so as to fit into a recess C⁴ in the lid.

The bolt passes through a hole in the lid 50 and is formed on, secured to or passed through a plate E', secured on the under side of the lid by screws or the like in the ordinary manner.

The parts are secured together in the 55 closed position by a screw cap F of such size as to overlap the free ends of the tapered

plates. To prevent the loss of the screw cap, a chain F' is secured to the cap and its free end is passed through a small hole in the lid and secured to or on the plate E' or to 60 one of the screws securing said plate to the lid.

Having fully described my invention, what I claim and desire to secure by Letters Patent is:—

1. A packing case comprising a body and a lid, a metallic strengthening band secured to the said body, fastening strips hinged to the upper ends of said band, tapered plates on the ends of said strips adapted when 70 closed down on the lid to leave a space between them, a threaded rod on the lid coinciding in position with the space left between the tapered plates, and a cap screwed on the threaded rod and overlapping the free 75 ends of the tapered plates and provided with means for securing it against accidental loss.

2. A packing case comprising a body and a lid, metallic strengthening bands secured 80 to the bottom and sides and bottom and ends of said body, fastening strips hinged to the upper ends of said bands, tapered plates on the ends of said strips adapted when closed down on the lid to leave a space between 85 them, a threaded rod on the lid coinciding in position with the space left between the tapered plates, and a cap screwed on the threaded rod and overlapping the free ends of the tapered plates and provided with 90 means for securing it against accidental loss.

3. A packing case comprising a body and a lid, metallic strengthened bands secured to the bottom and sides and bottom and ends of said body, fastening strips 95 hinged to the upper ends of said bands, tapered plates on the ends of the strips adapted when closed down on the lid to leave a space between them, said plates being stepped inward to fit into a recess in the 100 lid, a threaded rod mounted in the recess in the lid coinciding in position with the space left between the tapered plates, and a cap screwed on the threaded rod and overlapping the free ends of the tapered plates and 105 provided with means for securing it against accidental loss.

4. A packing case comprising a body and a lid, metallic strengthening bands secured to the bottom and sides and bottom and ends 110 of said body, fastening strips hinged to the upper ends of said bands, tapered plates on

the ends of the strips adapted when closed down on the lid to leave a space between them, said plates being stepped inward to fit into a recess in the lid, a threaded rod mounted in the recess in the lid and secured to a plate on the inner side of the lid, said rod coinciding in position with the space left between the tapered plates, and a cap screwed on the threaded rod and overlapping the free

ends of the tapered plates and provided with means for securing it against accidental loss.

In testimony whereof I have hereunto set my hand in presence of two subscribing witnesses this 25th day of January, 1921.

LIONEL WORSLEY HUGHES.
